(57) **CLAIM**

The ornamental design for an hourglass fork extender, as shown and described.

DESCRIPTION

FIG. 1 is a perspective view showing my new hourglass fork extender;

FIG. 2 is a left side view thereof;

FIG. 3 is a right side view thereof;

FIG. 4 is a front view thereof;

FIG. 5 is a back view thereof;

FIG. 6 is a bottom view thereof;

FIG. 7 is a top view thereof; and,

FIG. 8 is a view illustrating an example of the hourglass fork extender when attached to a fork of a motorcycle.

The broken lines illustrate portions of the hourglass fork extender and environmental structure that form no part of the claimed design.
